Primary Examiner—Doris V. Coles*Attorney, Agent, or Firm*—Loyal McKinley Hanson[57] **CLAIM**

The ornamental design for a fishhook remover, as shown.

DESCRIPTION

FIG. 1 is a top, front, and right side perspective view of a fishhook remover, showing my new design;

FIG. 2 is a left side view thereof;

FIG. 3 is a rear view;

FIG. 4 is an enlarged view similar to FIG. 1, with the handle portion of the fishhook remover foreshortened for illustrative convenience; and,

FIG. 5 is an enlarged bottom view.
